UNITED STATES PATENT OFFICE.

HENRY S. HOY, OF CHICAGO, ILLINOIS.

DUMP-WAGON.

No. 802,165.

Specification of Letters Patent.

Patented Oct. 17, 1905.

Application filed January 27, 1905. Serial No. 242,836.

To all whom it may concern:

Be it known that I, HENRY S. HOY, a citizen of the United States, residing at Chicago, in the county of Cook and State of Illinois, have 5 invented certain new and useful Improvements in Dump-Wagons, of which the following is a specification.

This invention relates to means for operating the drop-doors of dump-wagons; and its 10 general object is to provide improved means whereby the doors forming the whole or part of the bottom of a wagon or cart box may be supported and dropped upon the supports to release the load and subsequently raised to 15 clear the dump, all without undue strain upon the doors, to the end of permitting free removal of the wagon away from the deposited load.

One of the particular objects of the invention 20 is to provide operating means which are at once simple and positive in their action and which will act automatically to at least partially clear the drop-doors of the dumped load and utilize the latter to assist the same 25 means in guiding the doors when lifted up the outer sides of the box.

Another object of the invention is to provide improved connection between the bottom drop-doors and sides of the wagon-box to 30 secure adjustable automatic clearance of the doors, so that said clearance may be varied to suit special conditions; and my invention consists in the various details of construction and combination of parts, all as hereinafter 35 more fully described, illustrated in the drawings, and incorporated in the claims.

In the drawings, Figure 1 is a side elevation of a well-known type of dump-wagon with my invention applied thereto. Fig. 2 40 is a top plan view of the wagon shown in Fig. 1. Fig. 3 is a transverse section taken on line 3 3 of Fig. 1. Fig. 4 is an enlarged perspective detail view of one of the stops or guides. Fig. 5 is a detail view of the coupler 45 or clevis by means of which said guide is coupled adjustably to its supporting-chain. Fig. 6 is a view similar to Fig. 3, showing the position of the doors during their initial opening movements. Fig. 7 shows the doors 50 carried to their full-open position by the automatic arrangement. Fig. 8 illustrates how the doors may be still further raised up the sides of the box by means of the supporting-chains. Figs. 9, 10, and 11 illustrate modifications.

Referring now to the drawings in detail,

the wagon-box 2 may be of any well-known or approved form adapted for drop-doors 3 3'.

4 4' are straps bolted or secured to the door-cleats, and said straps have upturned portions 60 5 5', formed with eyes or holes 6 6', adapted to engage links or chains 7 7'. Said chains are anchored on brackets 8 8', secured to the outer sides of the box. The adjoining edges of doors 3 3' are supported on chains 9 9', secured to the doors at 10 10', respectively, and passing over pulleys 11 11', each mounted opposite an opening 12 in each side of the box on a bracket 13. The chains 9 9' then pass to a shaft or reel 14, provided with a crank or 70 ratchet lever 14'. A ratchet-wheel and pawl are usually provided, as at 14''. Upon each of the drop-doors are bolted, preferably two, stops 15, each of which is formed with a loop 16. In the upper part of each is a series of 75 holes 17, adapted to engage a lug 18 on the clevis or link 19, secured to each chain 20 or 20', anchored, respectively, at 21 21'. A hook 22 is formed at the opposite end of the stop to engage the edge of the door, to which said 80 stop is secured by means of a bolt 23 passing through apertures 24 25 in the stops or guides 15, the loops 16 of which are riveted at 24. When the wagon-box 2 is loaded with bulk material adapted to be unloaded by dumping, 85 doors 3 3' are sustained in their closed position by the chains 7 7' and 9 9'. By releasing the pawl from the ratchet-wheel the chains 9 9' will unwind, permitting the doors to drop under the weight of the load. As the 90 doors drop they swing pivotally at the ends of chains 7 7', which form the initial centers of pivotal movement, and as the curved loops 16 immediately begin to roll down the sides of the box they shorten the distances between 95 the sides of the box and the inner edges of the doors 3 3', which consequently also swing bodily away from each other during their downward swings about the ends of chains 7 7'. In other words, their movements 100 are substantially along a horizontal plane and in circular arcs, and the lengths of movements along said planes will equal the radii of curvatures of loops 16. By increasing the curvature of the loop the latter movement 105 will be increased to an extent equaling the increase of length in the radius of the loop arc, and referring, further, to the operation of one of the loops, which will describe all, when the terminus of the curvature of said 110 loop is reached under lateral pressure of the load the door will hang substantially parallel

with the sides of the box, and the under side of stop 15 serves as a runner upon which the door slides upward or in its edgewise movement. The pressure of the load between the adjacent edges of the drop-doors tends to force the runners or loops 16 up the inner sides of the box, which sides have then become inclines relatively to the stops. The chains 20 20' when the doors are in their closed position have sufficient slack in them to permit the "combination rollers and runners," as the stops 15 may be called, to roll against the sides of the box until the upper surfaces of the doors have moved away from the lower edges of the box far enough to allow the doors to swing around said lower edges on centers located at points of attachment of chains 20 20' to stops 15. The chains 20 20' then arrest the downward rolling movements of loops 16 and cause them to slide upward while still rolling in frictional contact with the sides of the box, tending to move them downward. While rolling down the sides of the box free from interference of chains 20 20', the centers of rotation, however, were the same as the centers of the curvatures of loops 16, while the moment chains become taut the centers of rotation are shifted to the points in the arcs of said loops where the clevises are attached, and as the latter are in planes at right angles to the planes of the doors and the former planes intersect the doors at points removed from their outer ends it is obvious that said outer ends must swing upward around the lower edges of the box under pressure of the falling load a distance equal in each instance to the distance of the horizontal plane of the clevises from the outer edges of the doors when same have assumed their vertical positions.

In Fig. 9 I have shown modifications wherein in blocks 26, secured by bolts 27 to the end-gates of the box, are substituted for chains 20 20'. Said blocks are recessed to provide shoulders 28, engaging loops 29. When the doors are lowered, said loops become suspended upon the blocks instead of the chains 20 20', and the space between the top of each loop and its block when the door is closed represents the slack in the chain 20 or 20'. In both forms of the invention the doors are caused to hug closely the lower edges of sides 22, and therefore swing upwardly within narrower confines than doors which swing away from the sides of the box when moving upward. This economy of space is an important feature where unloading must be done in passages or between buildings where there is barely room for the wagon to pass.

By adjusting lugs 18 in different holes 17 the doors may be swung automatically varying distances up the sides of the box. When chains are coupled to holes farthest from the respective sides of the box, the doors will swing upward the maximum distances, and

vice versa. When the doors are closed, the weight of the load is borne entirely by chains 7 7' and 9 9', and by the time the slack is out of chains 20 20' the doors are acted upon by the falling load at angles, thereby swinging the doors from under the load with comparatively little strain upon chains 20 20', which may be termed "secondary" pivotal supports, while chains 7 7' and 9 9' may be termed "primary" pivotal supports.

In Fig. 11 is shown a modification wherein stop 15 is in the form of a bracket-arm 30, having a stud or pin 31 movable down an incline 32 on block 33 and confined by a strap 34.

The movements effected by the modified structures shown in Figs. 9 and 11 are essentially the same as those effected by the preferred construction shown in Figs. 1 to 8, inclusive, though more limited in scope.

In Fig. 10 is shown a stop 15', consisting of a plate of metal provided with a base-plate 35, which may be bolted or otherwise secured to the upper surface of a drop-door, either within the confines of the sides and end-gates or exteriorly of the box. The stop 15', however, is designed particularly for interior use, as its comparatively thin blade-like form is adapted to work in or through the material in which the guide or stop would be embedded.

In using the loop form I prefer to let the sides and bottom doors project beyond the end-gates and mount the guides or stops 15 on the doors outside of the box, as shown clearly in Fig. 2, so as to allow the mechanism to work free of any possible interference from the load or material. The stops 15 may be made more or less elastic to allow the loops 16 to yield when necessary away from the doors and sides of box as the doors begin to revolve around the lower edges of the box.

The clearance of the doors and partial raising thereof are effected automatically by the weight of the load above the doors and by the upward pressure of the pile or dump as it grows underneath the wagon when dumping is done on level ground, as in filling in or raising a ground-level. As the pile or dump grows underneath the wagon it tends to push the doors upward, and this automatic operation may under the action of certain forms of material carry the doors to their highest position against the outer sides of the box. The outer edges of the doors being suspended from chains 7 7' have limited horizontal swinging movements, and therefore move apart substantially along the plane of the bottom doors and substantially direct. These movements therefore accelerate their separation or opening on the usual indirect lines. This not only facilitates the prompt release of the load, but allows a wider opening between the doors for a given drop movement than when the vertical swinging movement alone is relied upon and sometimes permits the free dumping of an entire load with a very

little drop of the doors. This is an advantage where delivery is made into an inclined chute for shelled corn and other granular material. When the falling load has crowded the drop-doors into parallelism with the sides of the box, it will support them against inward swinging movement while under tension of the lifting-chains when same are rewound upon the reel to move the doors as high as they can travel up the sides of the box, the doors and stops serving as guides on both sides of each box side to hold the doors for movement parallel to said sides during the remainder of the upward travel. After the wagon is pulled away from the dump and the doors are dropped to their suspended level, Fig. 6, upward pull on chains 9' 9" will tend to swing the doors inwardly, and the rounded ends of the stops or guides 15 guide the doors to their closed position by serving as levers which pry the doors toward each other. When the doors are finally closed, the strains upon the guides, tending to separate the doors, are distributed longitudinally of the guides.

Having thus described my invention, what I claim as new, and desire to secure by Letters Patent, is—

1. In a dump-wagon, the combination with a wagon-box provided with a drop-door of guides 30 slidable up one face of a side of the box for guiding the door up the opposite face of said box.

2. The combination with a wagon-box provided with a drop-door, movable about the lower edge of one side of said box, of means 35 engaging one vertical face of said side for guiding the door up the opposite vertical face of said side.

3. The combination with a wagon-box, provided with a drop-door, of means causing the outer edge of the door to swing vertically under pressure of a falling load upon said door, and means for varying the height of swing of said door.

4. The combination with a wagon-box provided with a drop-door, of means supporting said door for pivotal movement, and means for guiding said door, against an inner vertical side of said box, to move bodily up an outer vertical side of the wagon-box.

5. The combination with a wagon-box provided with a pivoted drop-door, of stops upon said door, which are unattached to said box, which serve as vertical and horizontal guides 55 for said door, and means for opening and closing said door.

6. The combination with a wagon-box provided with a drop-door, of means for closing said door, means supporting said door for pivotal movement, and means upon said door coöperating with said box and weight of the escaping load for guiding said door alongside said box, said last-mentioned means being a device which slides against the side of said box.

7. The combination with a wagon-box of a

drop-door, movable pivot members connected with said box, means secured to said door, but free of said box, for guiding said door to swing about the lower edge, and parallel to the sides, of said box.

70

8. The combination with a wagon-box, provided with a drop-door, of means for lifting said door to its closed position, said means supporting one edge of the door, means for supporting the opposite edge of the door, 75 both said means permitting a horizontal swinging movement of the door, and guides, slideable upon a vertical side of said box, for limiting the horizontal swinging movement of said door and for guiding the latter toward a position parallel with, and up the side of, said box.

9. The combination with a wagon-box provided with a bottom, pivotally-supported, gravity drop-door, means for closing said 85 door and retaining same in its closed position, a guide, or guides, movable along an inner side of the box upon which said door is slideable up an outer side of said box.

10. The combination with a wagon-box provided with a pivoted drop-door, of stops upon said door serving as vertical and horizontal guides for said door, said stops supporting said door against a vertical side of the box for a combined swinging and sliding movement with relation to said box.

11. The combination with a wagon-box of a drop-bottom, hinge members supporting said bottom, when closed and during its initial opening movement, and auxiliary hinge members which relieve said first-mentioned hinge members prior to the complete opening movement of said door, said auxiliary hinge members supporting the door intermediate of its edges to swing the latter in opposite directions.

12. The combination with a wagon-box provided with a drop-door, and the means for supporting and lifting said door, of guides upon which said door may slide along the body of 110 the box, for guiding said door during its opening and closing movements.

13. The combination with a wagon-box provided with a drop-door, of means for supporting and swinging said door, means, independent of its normal pivotal connections for causing the weight of the escaping load to slide said door on the edge of one side of said box to its full open position against the outer side 115 of said box.

14. The combination with a wagon-box provided with a drop-door, of pivots upon which said door moves, means supporting said pivots for movement with said door and relative to said box, and means independent of said pivots and their supporting means for guiding the door up the side of the box when released under load.

15. The combination with a wagon-box provided with a bottom, pivotally-supported, 125

130

drop-door, of means for supporting and swinging said door pivotally, and means independent of said last-mentioned means for shifting the center of swinging movement toward the 5 falling edge of the door and toward the top of the box gradually shortening projection of said door underneath said box.

16. The combination with a wagon-box provided with a bottom, pivotally-supported, 10 drop-door, of means for closing said door and retaining same in its closed position, and means for checking the fall of said door when released prior to complete opening, said last-mentioned means shifting the axis of the 15 door's rotation to point between and above the initial axis and arc of rotation.

17. The combination with a wagon-box provided with a bottom, pivotally-supported, drop-door, of means for closing said door and 20 retaining same in its closed position and means for checking the fall of said door when released prior to complete opening, said last-mentioned means gradually shifting the axis of rotation of the door toward the falling, 25 and away from the pivoted, edge thereof.

18. The combination with a wagon-box, provided with a drop-door, arranged to open by swinging horizontally to one side of the box and sliding vertically against said side, of 30 means whereby the falling load imparts said movements to the door when the latter is released from its closed position.

19. The combination with a wagon-box having a drop-door hinged at its one edge to the 35 side of said box, means for closing said door, means relieving the hinge members of the weight of the door when the latter begins its opening movement and for gradually shortening the length of its opening swing and 40 cause said door to swing closely to the box when dropping under load.

20. The combination with a wagon-box having a drop-door hinged at its one edge to the side of said box, means for closing said door, 45 means relieving the hinge members of the weight of the door when the latter begins its opening movement and for gradually shortening the length of its opening swing and cause said door to swing closely to the box 50 when dropping under load, and means for varying the extent of such opening movement.

21. The combination with a wagon-box provided with a bottom drop-door, of means for closing said door, and retaining same in its 55 closed position, supports constituting slide-bearings upon said door by which the latter is movable bodily, up the outer side of the box, and flexible supports for said guides.

22. The combination with a wagon-box, provided with a bottom, drop-door, of means for closing said door and retaining same in its closed position, fixed supports constituting slide-bearings upon which said door is automatically slid up the outer side of the box by

the action of the falling load, flexible supports 65 for said fixed supports, and means for adjusting said flexible supports to vary the extent of automatic sliding movement.

23. The combination with a wagon-box provided with a bottom, drop-door, of means for closing said door and retaining the same in its closed position, guides secured to said door and free of said box, flexible supports connecting said guides and box, said guides bearing against one vertical face of one side of the 75 box to force the door automatically up the opposite face of said side under the weight of the falling load.

24. The combination with a wagon-box provided with a drop-door, stops upon said door, 80 engaging one side of said box, and co-operating with the hinge members to support said bottom when closed against edgewise movement, said stops arranged to guide said bottom upward, during its opening movement 85 against one of the vertical sides of the box, and means for operating said bottom upon said stops and hinge members.

25. The combination with a wagon-box provided with a drop-door, of a reel and flexible 90 connection for operating said door and retaining same in a closed position, primary and secondary pivotal side supports for said door adapted to engage the opposite vertical faces of one side of said box said primary pivotal 95 supports arranged to lower said door to clear the lower edge of the box side, said secondary pivotal supports serving to elevate the door's center of rotation and as guides upon which said door is slid up the side of the box under 100 the weight of the load after release of said retaining means.

26. The combination with a wagon-box having a drop-door, of means for supporting the opposite edges for said door in its wide-open 105 and closed positions, means for supporting said door intermediately of the edge-supporting means and to dispose the center of gravity of the falling load to cause the latter to swing said door around the edge and up the 110 side of the box independently of the edge-supporting means.

27. The combination with a wagon-box having a drop-door, of means for supporting said door for pivotal movement, means for lifting 115 said door to its closed position, and means for changing its center of pivotal movement relatively to itself and to the box side about which said door swings to cause the falling load to swing the opposite edges of said doors 120 in opposite directions utilizing the side of the wagon-box as an auxiliary guide.

28. The combination with a wagon-box provided with a bottom, pivotally-supported, gravity drop-door, of supporting members for 125 said door comprising a chain and reel and hinge members and guides upon the door which utilize one vertical face of one side of the box

as an incline up which the door is slid against the opposite face of said side, and flexible connections between said guides and box which control the operation of said guides.

5 29. The combination with a wagon-box provided with a pair of drop-doors, of means for closing said doors, and means upon said doors operating against adjacent sides of the box for guiding said doors against the sides of said box during their swinging movement.

10 30. The combination with a wagon-box provided with drop-doors, of means for closing said doors, means supporting said doors for movement about the lower edges of the sides 15 of said box, said closing means coöperating with said supporting means to guide said doors along the vertical planes of the sides of said box.

15 31. The combination with a wagon-box provided with drop-doors, means for closing said doors, movable pivots upon which said doors swing, and means permitting said doors to move about their pivots and with their pivots in a compound rotary and sliding movement 25 from their closed positions to the outer sides of said box.

20 32. The combination with a wagon-box provided with drop-doors, of pivots upon which said doors move, means supporting said pivots 30 for movement with said doors and relatively to the sides of said box, and means independent of said pivots and their supporting means for lifting and guiding the door up the sides of said box when released under the load.

25 33. The combination with a wagon-box provided with bottom, pivotally-supported, gravity drop-doors, of means for closing said doors and retaining same in their closed positions, and pivotal connecting means between said 40 doors and box, confined within the vertical plane of the latter, providing for bodily movements of said doors up the outer sides of said box and beyond its vertical plane and so disposing the centers of gravity of said doors, 45 when hanging free in their normal positions,

as to insure proper closure upon operation of said closing means.

34. The combination with a wagon-box provided with outwardly-swinging, drop-doors, of chains attached thereto to close said doors 50 and retain same in their closed positions, a reel upon which said chains are wound, pivotal connections between said doors and box providing for free vertical movements of said doors up the outer sides of said box, stops, 55 bearing against the adjacent faces of the sides of the box, coöperating with said pivotal connections to hold the doors, when closed, against edgewise movements, flexible connections between said stops and box, said stops and flexible 60 connections coöperating with the escaping load to relieve said pivotal connections of the weight of the doors and to move said doors up the outer sides of the box.

35. The combination with a wagon-box provided with outwardly-swinging, drop-doors, of chains attached thereto to close said doors and retain same in closed positions, a reel upon which said chains are wound, stops upon said doors bearing against the inner walls of the 70 sides of the box, said stops coöperating with the pivotal connections for said doors to hold the latter against movement when closed, means for checking the fall of said doors and pivotally suspending said stops prior to completion 75 of the opening movements of said doors, said stops then supporting the doors for rotary movements about axes intermediate of the longitudinal edges of said doors and guiding said doors under pressure of load, when released, 80 toward vertical positions overlapping the outer sides of the box.

In witness whereof I have hereunto set my hand in the presence of two subscribing witnesses.

HENRY S. HOY.
